UNITED STATES PATENT OFFICE

RICHARD BERNHARD, OF ALLENTOWN, PENNSYLVANIA, ASSIGNOR TO TRAYLOR ENGINEERING & MFG. CO., OF ALLENTOWN, PENNSYLVANIA, A CORPORATION OF DELAWARE

ROTARY TUBE COOLER

Application filed June 9, 1928. Serial No. 284,126.

My said invention relates to cooling apparatus designed more especially for cooling materials having a material dust content which it is desirable should be prevented from escaping into the open air, or which, by the value of such dust content, calls for its collection and utilization.

Calcined zinc ore, iron ore, magnesite and caustic lime may be mentioned as examples of such materials.

The invention aims to provide a cooling apparatus which will be simple, economical of production and operation, durable and highly efficient.

15 The invention further aims to provide a construction in which the ore will be segregated into a considerable number of separated portions subjected to individual cooling action, and in which escape of dust from 20 the cooler into the surrounding atmosphere or loss of such dust will be prevented.

25 The invention further aims to provide a cooler having maximum capacity and which will enable the rapid and efficient cooling of materials which suffer more or less injury when subjected to excessive agitation, such as repeated lifting and showering or dropping as occurs in the type of rotary drum coolers heretofore used, and which will keep 30 such materials free from oxidation and other chemical reactions due to contact with the oxygen of the atmosphere.

With these and other objects in view, which will hereinafter appear, the invention comprises the novel construction hereinafter described and defined by the appended claims.

What I at present consider the preferred embodiment of the invention is illustrated in the accompanying drawings in which:

40 Fig. 1 is a central vertical longitudinal section through the cooler, partly broken away.

Fig. 2 is an elevation of the feed end thereof, and

45 Fig. 3 is a similar view of the discharge end, but partly in section.

Referring by reference characters to these drawings, my cooler is shown as comprising tube plates 1 and 2 with suitable openings in which are firmly secured, as by welding or 50 other desired means, an annular series of

tubes 3. These tube plates project beyond the outer peripheral portions of the tubes, plate 2 for a greater distance, the purpose of which will hereinafter appear. An end closure head 4 for the feed end has its major (central) portion of conical or flaring shape to provide a material receiving chamber adjacent the feed ends of the tubes, said head having a marginal flange 4^a lying in a plane perpendicular to the axis of the cooler which flange overlies the outer portions of the tube ends and abuts against the same. The peripheral edge of the flange is bolted or otherwise suitably secured to the margin of the tube plate 1.

55 The central portion of said closure head is provided with a tubular extension or feed eye 4^b which is journaled in a suitable bearing 5 supported by the wall of the water tank 6.

60 A feed chute 7 leads through this tubular portion or eye to deliver the material to the cooler, sealing means 8 being provided to prevent the escape of dust between the feed chute and tubular part 4^b. The material may be supplied from any suitable source, such for 65 example as hopper 9, and is fed from the hopper to the feed chute by the bladed feed wheel 10 which delivers the material to the feed chute uniformly and continually as required. The feed wheel 10 is driven by sprocket gearing 10^a from the drum extension 4^b and the 70 speed of the feed wheel may be varied by changing the sprockets.

75 As the material drops from the feed chute into the space within the closure head 4, it 80 descends to the bottom thereof and enters the end lowermost tube where it is picked up by its helical conveyor blade 3^a and conveyed along the annular space between the inner 85 wall of the tube and the central cylindric rod 3^b as the tube revolves.

90 The tank is filled with water to the level indicated in Fig. 1, by which the tube is cooled, being entirely surrounded by the water. As the tubes rise successively out of the water, they are subjected to further cooling action by water sprayed thereon from horizontal pipe 20 having spray openings in its under side, which pipe may be supplied with water 95 from any suitable source not shown. This 100

spray water acts on the tubes when they reach the top of their circle of movement, the water flowing down and around the outside surface of the tubes and efficiently cooling the 5 same, because of the rapid evaporation of the cooling water.

The discharge end of the cooler is provided with a closure head 12, likewise of substantially conical shape having a peripheral flange 10 12^a (offset from the margin of the cone) which is bolted or otherwise suitably secured to the marginal portion of the tube plate 2, such conical portion having a tubular extension 12^b which is journaled in the bearing member 15 13 and forms a journal support for the delivery end of the cooler.

The marginal portion of the head 12 carries an annular gear 14 which enables the cooler to be conveniently driven from any 20 suitable source of power through drive shaft 15 and spur gear 16 meshing with gear 14. Said gear is preferably enclosed by a gear housing 18.

The central portion of the tube plate 2 carries a conical projection 2^a, the apex of which is located centrally of the discharge eye or tubular extension 12^b, and such spreader carries a plurality of radially arranged blades 12^c. These serve to lift the material, 25 30 charged from the cooler tubes into the lower portion of the space defined by the cone shaped parts, 2^a and 12, until it is in a position above the axis of rotation of the cooler when it will be delivered by gravity through 35 the discharge eye.

The discharge eye or tubular part 12^b delivers the material into a closure chamber 19 having a discharge spout 19^a which may be provided with a gravity opening closure 40 member at 19^b not shown.

A cooler constructed as above described is extremely efficient in operation.

The material passing through the cooler is divided into a plurality of isolated bodies 45 as it passes through the individual tubes, and the cooling thereof is effected by convection of heat to the water when the tubes are submerged, and also by the chilling effect of the sprayed water on the unsubmerged tubes and 50 the evaporation therefrom, and due to the fact that the ore, during the cooling, is passed through a plurality of relatively small tubes, the surface exposed to the cooling action is very largely increased over what would be the 55 case with the use of a single cooling drum as heretofore commonly used.

Further, as the ore is confined in such relatively small tubes and conveyed therein by the helical conveyors, dropping or showering of the material is avoided and there is therefore no excessive agitation or impact action thereon, and at the same time, the material is kept free from oxidation by atmospheric 60 65 action and escape of dust content is prevented.

Having thus described my invention, what I claim is:

1. A cooler comprising hollow receiving and delivery heads mounted to rotate about a horizontal axis, a plurality of annularly 70 arranged isolated cooler tubes connecting said heads and having individual conveyor means associated with each tube for effecting passage of material through the tubes, means for rotating said cooler and means for bringing a cooling liquid into contact with said tubes as they revolve.

2. Apparatus according to claim 1 in which means is provided for spraying water on the tubes. 80

3. A cooler comprising tube plates having annularly arranged spaced openings, tubes having their ends rigidly held in said openings, receiving and discharge substantially 85 cone shaped closure heads having their margins secured to the margins of the tube plates, means for rotating the assembly, means for feeding material into the receiving head, means within the tubes for effecting travel of material through the tubes during their orbital movement, means for effecting delivery of material from the discharge head and a water tank into which the tubes pass during their orbital movement. 90

4. A cooler comprising tube plates having 95 annularly arranged spaced openings therein, cooling tubes having their ends rigidly held in said openings, hollow closure heads having margins secured to the margins of said tube plates, said heads having tubular extensions forming trunnions journaled in suitable bearings, and helical conveyor blades rigidly held within said tubes, the closure head at the intake end of the cooler comprising means for closing the outer portions of 100 105 the ends of the tubes.

5. A cooler comprising tube plates having 110 annularly arranged spaced openings therein, cooling tubes having their ends rigidly held in said openings, hollow closure heads having margins secured to the margins of said header plates, said heads having tubular extensions forming trunnions journaled in suitable bearings, said tube plate at the discharge end of the cooler having a cone shaped extension with its apex disposed adjacent the center of the discharge 115 trunnion, and radial blades carried by said extension.

6. A cooler comprising header plates having 120 annularly arranged spaced openings therein, cooling tubes having their ends rigidly held in said openings, hollow closure heads having margins secured to the margins of said header plates, said heads having tubular extensions forming trunnions 125 journaled in suitable bearings, said header plate at the discharge end of the cooler having a cone shaped extension with its apex disposed adjacent the center of the discharge trunnion, and radial blades carried by said 130

extension, and a sealed delivery chute leading from said discharge trunnion.

7. A cooler comprising hollow heads having hollow feed and discharge trunnions, a plurality of annularly arranged tubes having their ends in communication with said heads, helical conveyor blades in said tubes, means for rotating said heads and tubes, and means for feeding material to and discharging it from said heads.

10 8. A cooler comprising hollow heads having hollow feed and discharge trunnions, a plurality of annularly arranged tubes having their ends in communication with said heads, helical conveyor blades in said tubes, means for rotating said heads and tubes, and means for feeding material to and discharging it from said heads respectively, and means for subjecting said tubes to the 20 action of a cooling medium during their revolution.

9. A cooler comprising hollow heads having tubular feed and discharge trunnions, a plurality of annularly arranged tubes having their ends communicating with said heads, means for rotating said heads and tubes, means within said tubes for effecting travel of material through said heads during their period of revolution, a feed chute 30 for delivering material through the feed trunnion, closure means between said feed chute and trunnion, and a water tank through which said tubes pass in their orbital movement.

35 10. A cooler comprising hollow receiving and delivery heads, a plurality of annularly arranged isolated cooler tubes connecting said heads, and having individual means associated with each tube for effecting passage 40 of material through the tubes, means for rotating said cooler, and a water tank beneath the cooler, into the water of which the tubes are successively submerged.

11. A cooler comprising hollow receiving 45 and delivery heads, a plurality of annularly arranged isolated cooler tubes connecting said heads, helical conveyor blades within the heads, and means for rotating heads and tubes.

50 12. A cooler comprising hollow receiving and delivery heads, a plurality of annularly arranged isolated cooler tubes connecting said heads, means within said tubes for effecting passage of the material to be cooled 55 through said tubes in segregated batches during the orbital movement of the tubes, means for rotating said heads, and means for applying a cooling liquid to the exterior of said tubes during their orbital movement.

60 In testimony whereof, I affix my signature.
RICHARD BERNHARD.
